PHILIP D. PARSONS, OF PHILADELPHIA, PENNSYLVANIA, ASSIGNOR TO SCOTT PAPER COMPANY, A CORPORATION OF PENNSYLVANIA.

PAPER TOWEL FOR TOILET PURPOSES.

1,158,548.

Specification of Letters Patent.

Patented Nov. 2, 1915.

Application filed March 27, 1915. Serial No. 17,409.

To all whom it may concern:

Be it known that I, PHILIP D. PARSONS, a citizen of the United States, and resident of Philadelphia, county of Philadelphia, and 5 State of Pennsylvania, have invented an Improvement in Paper Towels for Toilet Purposes, of which the following is a specification.

This invention relates to paper towels for 10 toilet purposes and has for an object to provide a package of folded paper towels which shall be compact and suitable for use within a serving cabinet in such manner that individual towels may be successively withdrawn 15 as desired.

More particularly the object is to provide a package of paper towels each of which is so folded and arranged as to provide a positive and effective folded part or means 20 to be engaged by a discharging blade operatively mounted upon the cabinet whereby exterior manipulation of the said blade causes the said folded part to be readily engaged and pushed through the discharge 25 opening of the cabinet, where it may be grasped and the towel withdrawn without objectionably disturbing the remainder of the towels within the cabinet.

More specifically, the folded towel sheet 30 may be considered as having a main fold which forms a body part of multiple ply or thickness and which in turn has two opposite ends provided with folded parts one of which serves as a spacing element to obtain 35 uniformity in the package, and the other provides the aforesaid folded part or means located in the path of movement of the discharging blade or ejector.

With the above and other objects in view, 40 the nature of which will be more fully understood from the description hereinafter the invention consists in the novel construction of paper towels as hereinafter more fully described and defined in the claims.

Referring to the drawings: Figure 1 represents a sectional elevation of a portion of the serving cabinet showing the adaptation of my improved paper towel thereto; Fig. 2 represents a side elevation of the towel 50 sheets folded and arranged in package form in accordance with my invention; Fig. 3 represents a similar elevation of a package of the sheets having a modified form of

fold; and Fig. 4 represents a perspective of a portion of one of the towel sheets, shown 55 in Fig. 3.

Similar numerals of reference indicate corresponding parts.

1 designates a preferred type of cabinet for use with the towels of my invention and 60 has its lower part provided with a transverse slot 2 through which the towel tab or means to be engaged by the discharging blade 3 may be projected. The blade 3 may be of any desired form but as here shown 65 it is pivoted and arranged to be reciprocated by the lever 4. The cabinet may also have the shelf or shoulder 5 at the side opposite the blade for supporting the package of towels at one side and if desired the opposite side of the cabinet may be similarly provided with a support 6.

Referring more particularly to the folded paper towels illustrated in Figs. 2 and 3, a single towel is shown formed from a sheet 75 of paper doubled or folded back upon itself to form a multi-ply body part 7. In connection with this multi-ply fold it should be understood that this is the preferred form as the sheets may be folded in accordance with 80 my invention as a single sheet without the fold required to give multiple thickness, and I do not wish to be limited in this respect. One end of the body of the sheet is then folded at a suitable distance from its end to 85 form a spacing element 8 which is bent back upon the body of the sheet and in normal condition lies along one side of the body substantially in contact therewith and pointing in the direction of the opposite end of 90 the sheet. This element is designed to maintain the thickness of the sheet substantially the same and thereby provide a compact package when the successive folded sheets are positioned one above another in package 95 form. The length of this spacing element 8 may be varied according to requirements and also be folded to either side of the body part without departing from the present invention. In Fig. 2, I have illustrated the 100 preferred form wherein the spacing element 8 is folded in such a manner that it rests upon the top portion of the body of the sheet and it is therefore in such position that it contacts directly with the lower surface of the superposed sheet. In the modifi-

cation shown in Fig. 3 this spacing element or tab 8 is folded below the body of the sheet so that it lies along the lower surface thereof and consequently rests directly upon the body of the next lower sheet.

The opposite end of the sheet body is folded on a line as indicated at 9, parallel to the fold 10 of the spacing element 8 to provide a part 11 extending in a direction 10 toward the spacing element end of the body and lying in substantial contact with the lower surface of the sheet body. This part 11, after extending a suitable distance to provide a width of required size, is again 15 folded, reversely, at 12 on a line parallel to the fold 9, whereby the end or tab part 13 is directed toward the side of the cabinet and pointing in the same direction as the spacing element or tab 8. By this arrangement 20 it will be seen that the free edges 14 of the sheet terminate substantially against the walls of the cabinet and are held together between their juxtaposed sheets, or in case of the lowermost sheet between the supporting ledge and superposed sheets. The ends, therefore, are fixed in position and loose ends are consequently avoided. It will be noted, as each sheet becomes the lowermost 25 one of the package, that the fold 12, or reversely bent tab of multi-ply form comprising the part 11 and a portion of the end 13, assumes a position in the path of movement of the discharge blade 3, and therefore as the latter is operated, either manually or 30 mechanically, it will engage this tab portion 11, 13, and cause it to move with the blade toward and through the cabinet opening or slot 2 where it may be readily grasped and the sheet removed for use. Since the fold 12 35 naturally forms a closed end of multiple thickness it forms a positive and durable means to be engaged by the discharge blade and insures free removal from the cabinet without crumpling, crushing or rumpling 40 the sheet. Furthermore, it permits the lowermost sheet to be freely withdrawn without disturbing the remaining sheets of the package. I do not limit myself to the 45 size of the sheets, whether single or multi-ply, or to the character of material comprising 50

the sheets, as these may all be modified to suit the special requirements.

Having now described my invention, what I claim as new and desire to protect by Letters Patent is:

55

1. In a paper towel consisting of a sheet folded near one end on a line parallel to the opposite end, to form a reversely bent tab of multiple thickness below the body portion of the sheet, said tab extending parallel to the body of the sheet and having one of its plies projecting beyond the fold line of the sheet body, and the opposite end of the sheet being folded on a line parallel to the body fold for said multi-ply tab and forming a 60 spacing tab element pointing in the same direction as the aforesaid projecting end portion of the multi-ply tab.

65

2. A paper towel consisting of a sheet folded near one end on a line parallel to the opposite end, to form a reversely bent tab of multiple thickness below the body portion of the sheet, said tab extending parallel to the body of the sheet and having one of its plies projecting beyond the fold line of the 70 sheet body and the opposite end of the sheet being folded on a line parallel to the body fold for said multi-ply tab and forming a spacing tab element pointing in the same direction as the aforesaid projecting end portion of the multi-ply tab, said spacing element lying parallel to the body portion of the sheet and contacting with the top surface thereof.

75

3. A paper towel consisting of a sheet 80 folded on three parallel lines and providing two main tab portions pointing in the same direction parallel to the body of the sheet between said tab portions, and one of said tab portions having a reverse fold at its 85 union with the body portion and providing a multiple fold secondary tab pointing in the opposite direction to the main tab portions.

In testimony of which invention, I hereunto set my hand.

PHILIP D. PARSONS.
